(No Model.)

W. WATTIE.

PATTERN MECHANISM FOR LOOMS, &c.

No. 396,057.

Patented Jan. 8, 1889.

UNITED STATES PATENT OFFICE.

WILLIAM WATTIE, OF WORCESTER, MASSACHUSETTS, ASSIGNOR TO THE KNOWLES LOOM WORKS, OF SAME PLACE.

PATTERN MECHANISM FOR LOOMS, &c.

SPECIFICATION forming part of Letters Patent No. 396,057, dated January 8, 1889.

Application filed June 11, 1888. Serial No. 276,739. (No model.)

To all whom it may concern:

Be it known that I, WILLIAM WATTIE, a citizen of the United States, residing at Worcester, in the county of Worcester and State of Massachusetts, have invented certain new and useful Improvements in Pattern Mechanism for Looms, &c.; and I do hereby declare that the following is a full, clear, and exact description thereof, which, in connection with the drawings making a part of this specification, will enable others skilled in the art to which my invention belongs to make and use the same.

My invention relates to mechanism for operating pattern surfaces or chains in looms or other machines; and the object of my invention is to provide a positively-operated and comparatively simple organization of mechanical devices, by means of which certain bars in the pattern surface or chain may be repeated as desired without constructing successive similar bars. This result I accomplish by means of two pattern surfaces or chains, one main surface, which acts directly upon the loom or machine of which it is a part, and one auxiliary surface, the office of which is to keep up the motion in the parts while the main surface rests on the bars which it is desired to repeat. On the main pattern-surface, in addition to the indicators required for the machine, is a series of indicators which act upon the auxiliary pattern-surface mechanism in the same manner that the auxiliary surface acts on the main surface mechanism. Each of these pattern-surfaces is moved in my improvement by an independent star-wheel driven each by its own pin-wheel, and the pin-wheels are moved into or out of gear with their respective star-wheels, as indicated by the pattern-surfaces.

Referring to the drawings, Figure 1 is a side view of my improved movement. Fig. 2 is an end view, partly in section, on line XX, Fig. 1, looking in the direction of the arrow, same figure; and Figs. 3 and 4 are detail views.

In Figs. 1 and 2, 1 represents the frame of the movement fastened by tap-bolts 2 to the loom or machine, of which it forms a part, at 3. The main pattern-surface is here represented as a common form of chain made up of links 4, which connect bars 5, upon which

are strung rolls 6, and tubes 7, arranged according to the demands of the pattern. This chain is mounted upon a spool, 8, Fig. 4, the 55 bars entering notches 9, cut in heads 10, placed the proper distance apart on the spool to admit the desired number of pattern-rolls between them. The chain-spool 8 is fitted to turn freely upon the stud 11, fastened securely to the frame 1.

Fitted to turn freely upon the spool, clearing the ends of the pattern-bars 5, is a star-wheel, 12, which is confined on the spool laterally by means of the small flange 13 integral with the spool, and the collar 14, fast upon the outer end of the spool; also, fast in frame 1 is a stud, 15, which has mounted loosely upon it a gear-wheel, 16, confined on the stud by a head, 17. Bolted to the face of the gear 16 is a flange, 18, which carries a sleeve, 19, on the outer end of which, free to slide lengthwise on the sleeve, but compelled to rotate in unison with it by means of the feather 20, is a pin-wheel, 21, adapted to operate the star-wheel 12. The stud 15 and the sleeve 19 are made hollow to receive the rod 22, which is fitted to slide freely through the stud and sleeve. One end of the rod is screwed into the hub of the pin-wheel 21 and held in any given position by the check-nut 23.

Fast on the other end of the rod is a hand-hub, 24, provided with a groove, 25, into which is fitted loosely the yoke 26, which is engaged by the forked lever 27, pivoted at 28 on an arm, 29, cast on frame 1. On the top end of the lever 27, fitted to revolve loosely, is a roller, 30, which engages a cam, 31, mounted upon the hub 32 of flange 37, which is fitted to turn loosely on a stud, 33, fast in 90 frame 1. Cut in the cam 31 at suitable intervals, the determination of which is described farther on, are depressions 34, a trifle larger in outline than the roller 30. Cast integral with arm 29 is a socket, 35, which contains a coil-spring, 36, which is retained in the socket 35 by a corresponding socket, 37', on the forked lever 27. The power of the spring 36 is sufficient to slide the pin-wheel 21 on the sleeve and force the roller 30 into a 100 depression, 34, when the cam 31 is turned into the proper position.

The flange 37 on hub 32 has cut upon its periphery a series of star-wheel points, 38,

occupying the same angular space as the depressions in the cam 31, and adapting it to be driven by a pin-wheel formed on the end of the shaft 39, which is fitted to slide freely through a hollow stud, which holds the gear 40 in place on frame 1 in the same manner that the stud 15 holds gear 16. The pin-wheel 41, Fig. 3, is behind the star-wheel 38 in Fig. 2.

On the other end of shaft 39 from the pin-wheel is fastened a flanged hub, 42, in the flange of which is fast a pin, 43, fitted to slide freely in a hole in the hub of gear 40, thus acting the same as feather 20, compelling the pin-wheel shaft 39 to rotate in unison with the gear. The hub 42 is provided with a groove, 44, into which is fitted loosely a yoke, 45, similar to yoke 26 in hub 24. Yoke 45 is engaged by forked lever 46, which, with hub 47 and arm 48, forms a bell-crank, which is mounted loosely on a stud, 49, fast in an arm, 50, which projects from frame 1. Coiled on stud 49 is a spring, 51, one end of which is fast to the head of the stud 49 and the other end of which is hooked into forked lever 46.

The spring is put in tension by turning the stud 49, and held by set-screw 52, and is of sufficient force to slide pin-wheel shaft 39 through its stud. Depending from stud 53 on arm 48 is an adjustable link, 54, the lower end of which is socketed on the end of lever 55, pivoted on stud 56, fast in frame 1. Lever 55 is provided near the joint with link 54, with a foot, 57, which is fitted to engage the projecting ends of the indicator-bars 5 on the pattern-chain on spool 8, Figs. 1 and 4.

The projecting bar on the pattern-chain, through foot 57, lifts lever 55, and with it, through link 54, the arm 48 of the bell-crank, drawing the pin 58, Fig. 3, of pin-wheel 41 out of line with its star-wheel 38 and allowing end 59 of shaft 39 to rest in the dwell 60 of the star-wheel. The proper alignment of pin-wheel 41 with its star-wheel, with reference to the motion imparted by passing a projecting bar under lever 55, is effected by adjusting the length of link 54 by means of the socket-head 61 and threaded rod of the link 54. When a short bar is in position under the foot 57, the spring 51 acts to throw the pin 58 into line for engagement for star-wheel 38. Pin-wheel 21 is slid into and out of line for engagement with star-wheel 12 in a similar manner by means of the cam 31 and spring 36 through lever 27, and the alignment of pin 5 and star wheel is effected by screwing the rod into or out of the hub of the pin-wheel 21.

The gear 40 is driven by the gear 62, fast on a shaft, 63, which is a part of the loom or machine to which the frame 1 is attached, and motion is communicated to gear 16 through intermediate gear, 64, which runs loosely on a stud fast in the loom-frame 1; also, pivoted on stud 56 are a series of levers, 65, which extend out over the pattern-chain and are provided with feet 66, each fitted to engage a row of indicators on the pattern-chain. To the ends of the levers are pivoted links 67,

(shown broken off,) through which the indications of the pattern-chain are communicated to the loom or machine. It is frequently desirable to turn the main pattern-chain by hand without disturbing the other parts. To accomplish this, I form in the loose star-wheel 12 a series of sockets, 68, located the same angular distance apart as the points of the star-wheel, and in the collar 14, fast on the chain-spool, a socket, 69, on the same circle with the centers of sockets 68 in the star-wheel. Free to slide in the socket 69 is a pin with a head, 70, at the inner end, which fills the socket, and provided with a spindle, 71, which projects through a hole the size of the spindle in the shell at the end of the socket.

Confined between the head of the spindle and the end of the socket is a spring, 72, coiled on the spindle, which is of sufficient force to keep the pin in the socket with which it coincides in the star-wheel. When in this position, motion is transmitted by the star-wheel from the pin-wheel to the chain-spool through the fast collar 14. Fastened to the projecting end of the spindle is a handle, 73, by which the pin may be withdrawn from the sockets in the star-wheel, when the chain may be turned by hand, the star-wheel being held by the pin-wheel, the spool turning within it. Whenever, for the purpose of picking out imperfect work or otherwise, it is desirable to turn the main pattern-chain by hand, as just described, it will be necessary to turn the auxiliary cam 31 to correspond, or the main and auxiliary pattern-surfaces would get out of time with each other. To accomplish this, I mount the cam 31 loosely on the hub 32, where it is confined by collar 74. On the flange of the cam 31, I form a spring-pin socket, 75, in which a pin, 76, works in conjunction with sockets 77 in the flange 37 in the same manner as pin 70 73 in socket 69 with star-wheel 12. Sockets 77 are the same angular distance apart as the points of star-wheel 38. When the pin 76 is in the position shown in Fig. 2, the cam 31 will be driven by star-wheel 38 and pin 76 may be withdrawn, allowing the cam to be turned independently of the star-wheel.

I use the projecting end of bars 5 in the main pattern-chain to indicate the movements of pin-wheel 41 instead of the regular tubes and rolls, in order to save chain-stock. The work of sliding the pin-wheel shaft is so slight that I experience no difficulty in doing this. It will be further noticed by reference to Fig. 2 that I use the same bar by reversing it, either for a projecting bar to act on foot 57, or for a short bar to clear foot 57, the projecting end when reversed passing the indicating-point idly. I thus avoid the confusion in building chain that would be incident to having two lengths of bars, beside saving chain-stock again.

The parts are so timed that the pin-wheel on shaft 39 has just finished its action on the star-wheel 38 when pin-wheel 21 comes into

engagement with its star-wheel 12, and the time occupied by the action of both pin-wheels is something less than one complete revolution of the pin-wheels or of the shaft 63, the 5 gears 16, 40, and 62 being all the same size.

The operation is as follows: The parts being in the position shown in the drawings, the pin-wheel 21 being in engagement and just beginning its action on the star-wheel 12, 10 the action of pin-wheel 21 moves star-wheel 12 and with it the main pattern-chain, one angular space bringing a bar which it is desired to repeat under the levers 65 and having a short bar in the row of indicators which 15 act on lever 55. The short bar calls down link 54, which allows spring 51 to push pin-wheel 41 through forked lever 46 into engagement with star-wheel 38. Continuing the revolution, pin-wheel 41 moves star-wheel 38 20 one angular space, which lifts roller 30 out of a depression in cam 31 and onto the face of the cam, which, through forked lever 27, slides rod 22 and moves pin-wheel 21 out of engagement with its star-wheel 12, leaving the dwell 25 end of the pin-wheel hub in line with the star-wheel. Pin-wheel 21 being out of engagement, the succeeding revolution of the parts does not move the main chain-shaft, and the same bar is repeated. Pin-wheel 41 will continue 30 to move its star-wheel one space each revolution, as long as no depression comes opposite roller 30 on cam 31; and the ends of the next presented bars do not project to hold the lever 55 in its elevated position, and the number 35 of repeats desired determines the number of angular spaces on cam 31 which are to be left full face. When this number has been reached, a depression in cam 31 throws pin-wheel 21 into engagement, and at the succeeding 40 revolution the main chain is turned one space. The main chain can be kept in motion for as many succeeding revolutions as desired by putting projecting bars in the row of indicators which act on lever 55, thereby 45 keeping pin-wheel 41 out of engagement with its star-wheel. The main chain can be also kept in action by cutting depressions in the successive spaces on cam 31. The star-wheel 38 may be made with any convenient number 50 of points, and the main pattern-bars repeated, according to the number of points in said star-wheel.

Having thus described my invention, what I claim as new, and desire to secure by Letters 55 Patent, is—

1. The combination, with a series of levers and connections to a loom or other machine, of a main pattern-surface, star-wheel, sliding pin-wheel, hollow pin-wheel stud supporting 60 a driving-gear in train, and said driving-gear and means for actuating the same, hollow sleeve fast to said gear, adjustable connecting-rod passing through said hollow stud and sleeve and means for adjusting said rod, 65 spring-actuated rocker-lever, and an aux-

iliary pattern-surface, star-wheel, sliding pin-wheel driven by a gear in train, and said gear and means for actuating the same, hollow pin-wheel stud supporting said gear, spring-actuated bell-crank, adjustable connector, and pattern-lever, substantially as shown and described. 70

2. The combination, with a series of levers and connections to a loom or other machine, of a main pattern-surface, shaft carrying said pattern-surface, star-wheel loose on said shaft and provided with a series of sockets the same angular distance apart as the pattern-bars, collar fast on said shaft, spring-actuated pin socketed in said collar, sliding pin-wheel, 75 pin-wheel stud, sleeve, gear in train and means for actuating the same, connecting-rod, rocker-lever, and an auxiliary pattern-surface, star-wheel, sliding pin-wheel and connections between said pin-wheel and gear in 80 train, and said gear in train and means for actuating the same, pin-wheel stud, bell-crank, connector, and pattern-lever, substantially as shown and described. 85

3. The combination, with a series of levers and connections to a loom or other machine, of a main pattern-surface, shaft carrying said pattern-surface, star-wheel loose on said shaft and provided with a series of sockets the same angular distance apart as the pattern-bars, collar fast on said shaft, spring-actuated pin socketed in said collar, sliding pin-wheel, 90 pin-wheel stud, sleeve, gear in train and means for actuating the same, connecting-rod, rocker-lever, and an auxiliary pattern- 95 bars, collar fast on said shaft, spring-actuated pin socketed in said collar, sliding pin-wheel, pin-wheel stud, sleeve, gear in train and means for actuating the same, connecting-rod, rocker-lever, and an auxiliary pattern- 100 cam loose on an auxiliary star-wheel and provided with a spring-actuated pin socketed on said cam, auxiliary star-wheel provided with a series of sockets the same angular distance apart as the points and indications on cam, 105 sliding pin-wheel and connection between said pin-wheel and gear in train, and said gear in train and means for actuating the same, pin-wheel stud, bell-crank, connector-rod, and pattern-lever, substantially as shown and described. 110

4. The combination, with a series of levers and connections to a loom or other machine, of a main pattern-surface made up of links, 115 rolls, tubes, and reversible projecting bars, star-wheel, sliding pin-wheel, pin-wheel stud, sleeve, gear in train and means for actuating the same, connector-rod, and rocker-lever, and an auxiliary pattern-surface, star-wheel, 120 sliding pin-wheel, and connections between said pin-wheel and gear in train, and said gear in train and means for actuating the same, pin-wheel stud, bell-crank, connector, and pattern-lever, substantially as shown and described. 125
